US00D893235S

(12) **United States Design Patent** (10) **Patent No.:** **US D893,235 S**
(45) **Date of Patent:** **** Aug. 18, 2020**

(54) **DISPENSER**

(71) Applicant: **PepsiCo, Inc.**, Purchase, NY (US)

(72) Inventors: **Martin Eduardo Broen**, New York, NY (US); **Stephen Lim**, Chappaqua, NY (US); **Klaus Rosburg**, Brooklyn, NY (US); **Gustavo de Souza Messias**, Milan (IT); **Martin Ivar Franzen**, Milan (IT)

(73) Assignee: **PepsiCo, Inc.**, Purchase, NY (US)

(**) Term: **15 Years**

(21) Appl. No.: **29/720,407**

(22) Filed: **Jan. 13, 2020**

Related U.S. Application Data

(63) Continuation of application No. 29/647,697, filed on May 15, 2018, now Pat. No. Des. 873,071.

(51) **LOC (12) Cl.** **07-01**

(57) **CLAIM**

The ornamental design for a dispenser, as shown and described.

DESCRIPTION

FIG. 1 is a top front perspective view of a dispenser showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 5 Drawing Sheets
